CLAIM

The ornamental design for a six-cell beverage box with top flaps, as shown and described.

DESCRIPTION

FIG. 1 is a front perspective view of the claimed design shown with a top portion of the six-cell beverage box with top flaps positioned in an open configuration and a telescoping portion of the six-cell beverage box with top flaps positioned in an extended configuration.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is a plan view of a box blank that can be assembled to form the six-cell beverage box with top flaps of FIG. 1. FIG. 9 is a top perspective view of the six-cell beverage box with top flaps shown with the top portion in the open configuration; and,

FIG. 10 is a front perspective view of the six-cell beverage box with top flaps with the telescoping portion positioned in a retracted position and the top portion in a closed configuration.

The broken lines, the areas within them, and the areas bounded by both broken lines and solid lines depict portions of the six-cell beverage box with top flaps that form no part of the claimed design.
